(57) **CLAIM**

The ornamental design for a luminaire, as shown and described.

DESCRIPTION

FIG. 1 is a exploded front perspective view of a luminaire having a radially oriented light source according to the present invention.

FIG. 2 is a top plan view of the luminaire having a radially oriented light source illustrated in FIG. 1.

FIG. 3 is a side elevation view of the luminaire having a radially oriented light source illustrated in FIG. 1.

FIG. 4 is a cross sectional view of the luminaire having a radially oriented light source illustrated in FIG. 1 taken through line 4-4 in FIG. 3; and,

FIG. 5 is a exploded perspective view of the luminaire having a radially oriented light source illustrated in FIG. 1.

The dashed lines depict an enclosure that forms no part of the present invention.
